UNITED STATES PATENT OFFICE.

CLARENCE W. DICKINSON, OF WARREN, OHIO, ASSIGNOR TO THE YOUNGSTOWN
PRESSED STEEL COMPANY, OF WARREN, OHIO, A CORPORATION OF OHIO.

METHOD OF PRODUCING RIBBED EXPANDED METAL LATHING.

Application filed March 8, 1921. Serial No. 450,842.

To all whom it may concern:

Be it known that I, CLARENCE W. DICKINSON, a citizen of the United States, and resident of Warren, in the county of Trumbull and State of Ohio, have invented certain new and useful Improvements in Methods of Producing Ribbed Expanded Metal Lathing, of which the following is a specification.

10 My present invention relates to an improved method of producing expanded metal lathing and aims to provide a simple and efficient process which will produce a lath having longitudinal parallel portions inclined to the general plane of the sheet and other intervening connecting portions disposed substantially perpendicular to the plane of the sheet, all of said portions being formed of reticulated metal. The article 15 which is produced by my method is disclosed in and forms the subject of an application filed by me on the 2nd day of June, 20 1920, No. 385,896, Patent No. 1,372,741, dated March 29, 1921.

25 The invention includes the novel method hereinafter more fully described and particularly defined by the appended claims.

An embodiment of my invention is illustrated in the accompanying drawings in 30 which—

Figure 1 is a plan view of an expanded sheet before corrugating.

Fig. 2 is a section on line 2—2 of Fig. 1.

Fig. 3 is a plan view of the corrugated 35 sheet.

Fig. 4 is a section on line 4—4 of Fig. 3, and

Fig. 5 is an elevation, partly in section, 40 of a pair of roller dies capable of use in carrying out my improved process.

It will be readily understood that my method may be carried out by hand, if desired, but I prefer to use coacting dies, and preferably roller dies.

45 In proceeding according to my invention, I first provide a sheet of metal with longitudinally disposed rows of staggered slits which may be produced in the ordinary or any desired manner, these slits being uniformly distributed throughout the entire 50 area of the sheet between the margins thereof.

The sheet is then expanded by any suit-

able method or means to produce the form of expanded sheet shown in Fig. 1. 55

I then deflect certain of the strands a' and a'' in opposite directions vertically along equidistant longitudinal parallel lines, or lines parallel with the edges or margins of the sheet thus producing substantially vertical portions or ribs of reticulated nature, and at the same time carry, draw or press the intervening portions into planes which are inclined to the general plane of the sheet and which portions are also of reticulated 60 nature, being formed of the opened or expanded strands designated a'' .

The resulting lath may be said to comprise a plurality of longitudinal open work sections 1^b which lie in planes oblique to the 70 general surface of the lath, which sections are formed of sinuous strands extending lengthwise of the sections and connected together at separated alternating points, the adjacent edges of the sections being connected to one another by other sinuous strands extending between said adjacent edges and lying in planes substantially perpendicular to the sections, said connecting strands joining the strands of the oblique 75 sections at separated alternating points and securing a truss effect.

I prefer to deflect the strands as above described by means of coacting dies, preferably roller dies, as indicated at 2 and 2^a , 85 Fig. 5, journaled in suitable bearings 3, 3^a and geared to rotate in unison and to one of which power may be applied in any suitable manner. The die faces are provided with coacting faces which comprise substantially vertical portions or portions 90 lying in a plane substantially perpendicular to the axis of the die, and other portions extending in a diagonal or inclined direction from the inner edge of one vertical portion to the outer edge of the next adjacent portion.

Having thus described my invention, what I claim is:

1. The hereindescribed method of producing a ribbed expanded metal sheet from an expanded metal sheet formed of sinuous strands extending lengthwise of the sheet and connected together at separate alternating points which consists in deflecting certain strands in opposite directions substan- 100 105

tially vertically of the sheet along equidistant longitudinal parallel lines, and simultaneously carrying the intervening portions of the sheet into planes inclined to the general plane of the sheet.

2. The herein-described method of producing a ribbed expanded metal sheet from an expanded metal sheet formed of sinuous strands extending lengthwise of the sheet and connected together at separate alternating points which consists in deflecting certain strands in opposite directions substantially vertically of the sheet along equidistant longitudinal parallel lines, and simultaneously carrying the intervening portions of the sheet into planes inclined to the gen-

eral plane of the sheet, all of said intervening portions inclining in the same direction.

3. The herein-described method of forming corrugated lathing from a sheet having parallel longitudinal staggered slits, which consists in expanding such sheet and then feeding it longitudinally between coacting dies having longitudinally disposed pressing surfaces arranged at an obtuse angle to the plane of the sheet and other intervening surfaces substantially vertical to the general plane of the sheet.

In testimony whereof, I affix my signature.

CLARENCE W. DICKINSON.
